(**) Term: **14 Years**

(57) **CLAIM**

(21) Appl. No.: **29/189,225**

The ornamental design for a display holder for a ball or the like, as shown and described.

(22) Filed: **Aug. 28, 2003**

DESCRIPTION

(51) LOC (7) Cl. **08-08**

(52) U.S. Cl. **D6/552**

(58) Field of Search D6/513, 552, 567;
D3/254; 248/310-314, 309.1; 211/13.1,
14, 88.01, 89.01, 126.1; 206/557, 315.9

(56) **References Cited**

FIG. 1 is a perspective view of the invented display holder for a ball or the like showing the new design;
FIG. 2 is a bottom plan view thereof;
FIG. 3 is a rear elevational view thereof;
FIG. 4 is a left side elevational view thereof;
FIG. 5 is a top elevational view thereof;
FIG. 6 is a right side elevational view thereof; and,
FIG. 7 is a front plan view thereof.
